UNITED STATES PATENT OFFICE.

HENRY HENDRICKSON, OF TELLURIDE, COLORADO.

CALIPERS.

Application filed April 7, 1920. Serial No. 371,898.

To all whom it may concern:

Be it known that I, HENRY HENDRICKSON, a citizen of Sweden, residing at Telluride, in the county of San Miguel and State of Colorado, have invented certain new and useful Improvements in Calipers, of which the following is a specification.

This invention relates to improvements in calipers and its object is to provide calipers that can be easily and quickly adjusted and that are capable of taking and holding three separate and independent measurements at one and the same time. With the foregoing and other objects in view the invention consists in the combination and arrangement of parts to be hereinafter fully described, pointed out in the appended claims and illustrated in the accompanying drawing which forms a part of this specification and in which—

Fig. 1 is a plan view of my improved calipers.

Fig. 2 is an edge view of Fig. 1.

Fig. 3 is a section on line 3—3 of Fig. 1. Like reference characters denote corresponding parts throughout the several views.

My calipers comprise the main arm 1 having the handle portion 2 and the bifurcated end 3, the prongs 4, 5 thereof being curved in opposite directions and being unequal in size, the prong 5 being smaller than the prong 4, each of said prongs having the usual pointed terminations. To the prongs aforesaid the lesser arms 6, 7 are secured by the set screws 8, 9, said arms 6, 7 being bent or curved toward each other and their pointed extremities being adapted to cooperate with each other. The said arm 1 is formed with the elongated slots 10, 11 which diverge slightly from the handle portion 2 to the bifurcated end 3 and in the slot 10 a curved arm 12 is slidably and adjustably secured by the set screw 13, said arm 12

being adapted to cooperate with the prong 5 of the arm 1; and a curved arm 14 is slidably and adjustably secured to the slotted portion 11 by the set screw 15, the pointed end of said arm 14 being adapted to cooperate with the pointed end of the afore-said prong 4 of arm 1.

Three separate and distinct measurements may be taken with the tool by applying the arms 6, 7; the arm 14 and prong 4; and the arm 12 and prong 5 to the work. The arms 12, 14 being movable longitudinally of the arm 1 as well as adjustable pivotally permit a great variety of measurements to be taken by the tool and adapt it consequently to work of various kinds.

What is claimed is:

1. In calipers, a main arm having one bifurcated end, the prongs thereof being of unequal length and curved in opposite directions, said arms being formed with longitudinally extending slots, and means carried by said main arm for cooperation therewith, said means including a pair of independently adjustable arms slidably secured in the slots of said main arm.

2. In calipers, a main arm having one bifurcated end, the prongs thereof being of unequal length and curved in opposite directions, and a pair of lesser arms adjustably secured to the prongs of said main arm, said lesser arms being curved toward each other and being adapted to extend substantially beyond said main arm prongs in the plane of the body portion of the main arm.

In testimony that I claim the foregoing as my own I have hereto affixed my signature in the presence of two subscribing witnesses.

HENRY HENDRICKSON.
